UNITED STATES PATENT OFFICE.

EARL A. THOMPSON, OF PORTLAND, OREGON.

AUTOMATIC GEAR-SHIFTING MECHANISM FOR SLIDING-GEAR TRANSMISSIONS.

Original No. 1,435,430, dated November 14, 1922, Serial No. 221,412, filed March 9, 1918. Application for reissue filed January 3, 1924. Serial No. 684,174.

My invention relates to automatic gear-shifting means, and has among its salient objects to provide in combination with transmission gears adapted to be moved into and out of mesh with each other while they are turning, means for synchronizing the pitch line velocity of said gears, whereby to make it possible to easily move them into mesh with each other without gear clash; to provide in combination therewith a synchronizing mechanism adapted to be operated by the movement of the vehicle on which it is mounted; to provide in a mechanism of the character referred to a gear selecting mechanism for determining at will which of the transmission gears are to be moved into mesh with each other and on which the synchronizing mechanism is to operate before they are so moved; to provide in a mechanism of the character referred to a controlling member with connections for operating said mechanisms in proper sequence quickly and with ease.

My invention as I have worked it out and actually constructed it comprises, in combination with the usual clutch and transmission mechanisms of a motor car, a selector mechanism and a synchronizing mechanism. The selector mechanism has an indicating and operating member adapted to indicate the different speed connections possible, and when moved for this purpose, it also sets other mechanisms for moving the transmission gears, and the mechanisms for operating the synchronizer. The synchronizing mechanism is arranged to be driven by the movement of the vehicle on which it is mounted, and to impart to certain of the transmission gears a pitch line velocity substantially the same as the pitch line velocity of another transmission gear which is being driven by the movement of the vehicle and with which it is to be put into mesh, thus making it possible to move these gears into mesh with each other while they are turning without gear clash, because their speeds have first been coordinated.

I have connected the gear moving mechanism and the mechanism for controlling the operation of the synchronizing mechanism with the clutch operating member, whereby the simple movement of the clutch pedal, for example, not only disengages the clutch, but also disengages the transmission gears which

are in mesh with each other, causes the synchronizing mechanism to operate to co-ordinate the speeds of the gears previously selected to be put into mesh with each other, and also sets for action means for moving the selected gears into mesh with each other as the clutch pedal returns and the clutch again engages. The gear selecting mechanism can be set at any time independently of anything and without interfering with the driving connections already operating. In other words, it is only necessary, at any time before a change of gears may be necessary, to move the small selector member to the desired transmission connection—low, intermediate, or high—and when ready for the change, no matter at what speed you are traveling, to push in the clutch pedal and let it return and the entire change or shifting of the gears is accomplished. There is a sufficient lapse of time between the shifting of the gears into neutral by the forward movement of the pedal and the movement of the gears into mesh by the return movement of the pedal to allow for the proper synchronization of the gears to prevent any clash at the time that the gears are being meshed. Hand-operated transmission levers are done away with and the matter of shifting gears is made absolutely automatic by simply depressing the clutch pedal and allowing it to return.

In order to more fully explain my invention, I have shown on the accompanying sheets of drawings, for purposes of illustration, one practical embodiment thereof, which I will now describe.

Figure 1 is a top plan view of one embodiment of my invention.

Figures 2 and 3 are enlarged views of details.

Figure 4 is a side elevation of my invention with parts broken away and parts in section.

Figure 5 is a plan view of a selector element.

Figure 15 is a partial section view through the synchronizing mechanism shown in Fig. 12, showing an end elevation of one of the holding drums and its braking mechanism, and

20 Figure 16 is a top plan view of the holding drums and their braking mechanisms.

Referring in detail to the drawings, my invention comprises a casing for the clutch and transmission mechanism which is very 25 similar to that in common use, with certain extensions formed therein to receive the additional mechanisms constituting my invention. In the drawings, 1 designates the clutch casing, and 2 the transmission housing. Referring to Fig. 8, 3 designates the usual clutch driving shaft, 4 the clutch gear, 5 an internal gear adapted to be moved over the clutch gear 4 for direct drive, and 6 a gear for intermediate drive. Gears 5 and 6 30 constitute a single element slidably mounted on a square shaft 7, adapted to be locked to the clutch shaft 3, and to turn therewith, when the internal gear 5 is shifted over clutch gear 4. Secured to the gear 6, is a shifting collar 8, by means of which said gears 5 and 6 are moved in opposite directions. Also slidably mounted on the square shaft 7, is a gear 9, having a shifting collar 10. Also mounted in said transmission casing 45 is a counter shaft 11, provided with a gear 11^a secured thereto, and constantly in mesh with the clutch gear 4. Also mounted on said counter shaft 11, are three transmission gears 12, 13 and 14. 15 designates the 50 usual idler gear for reversing the drive. As this mechanism is well known, its operation need not be further described.

Referring now to Fig. 4, the usual clutch lever 16, is mounted on the usual shaft 17, in 55 the casing 2, for operating the clutch through the connecting elements 18, 19 and 20. The clutch lever 16, is secured to the end of the sleeve 21 mounted on said shaft 17, as clearly shown in Figs. 10 and 11. Said sleeve 21, 60 at its inner end, is cut away for one-half of its circumference, as indicated at 21^a. Also mounted on the shaft 17, at the inner end of said sleeve 21, is an arm 22, provided with a sleeve 23, also cut away to overlap the projecting end 21^a of the sleeve 21, as shown in

Fig. 10. The overlapping portions, however, of the sleeve 21, and of the sleeve 23, on said shaft 17, do not complete the full circumference of said sleeves, but are so arranged that there is a certain amount of lost 70 turning motion on the shaft 17, in order that the clutch lever 16, may be depressed sufficiently to release the clutch before the projecting sleeve portion 21^a, thereof, engages the projecting portion of the sleeve 23, in 75 such a way as to move the arm 22. The function of this arm 22, will be referred to more fully further on in this description.

Referring further to Fig. 4, I have mounted on the steering post 24, under the steering wheel 25, an operating member or lever 26, mounted on the upper end of an operating rod 27, extending through a tubular casing 28. Said operating member or lever 26, is 80 associated with a quadrant 29, secured to the steering post 24, as at 30. Said quadrant is provided with five indicating positions, or as many as may be required, there being shown, "R"—reverse, "L"—low, "N"—neutral, "I" 85 —intermediate, and "H"—high. The operating member or lever 26, is shown at neutral position in Fig. 5. This simple mechanism is operated to determine which of the transmission connections (low, intermediate, high, or reverse) is to be made.

90 The lower end of the operating rod 27, is bent at an angle, as at 27^a, more clearly shown in Fig. 6, to the end of which angle is connected an operating rod 31.

95 Referring now to Fig. 1, it will be seen that the opposite end of said rod 31, is connected to a bell crank 32, supported in a bracket 33, secured to the frame of the vehicle. The other arm 32^a of the bell crank 32, is adjustably connected by means of a link 34, to a 100 rack bar 35, adapted to be moved longitudinally different distances by the movement of the selector lever 26.

105 I will next describe the mechanism by means of which the transmission gears to be moved into mesh with each other are selected. Referring to Figs. 1, 9 and 10, the rack bar 35, is slidably mounted through the upper portion of an upper casing 36, mounted on top of the transmission casing 2, Fig. 1, the 110 cover of this upper casing being removed. Slidably mounted through said upper casing 36, are two parallel shafts 37 and 38. Rotatably mounted on said shafts 37 and 38, respectively, are two sleeves 39 and 40, the right hand end of said sleeves, as shown in Fig. 1, being provided with longitudinally extending gear teeth, 39^a and 40^a, adapted to mesh with said rack bar 35, whereby said sleeves 39 and 40, are rotated as said rack bar 35, is moved by the selector lever 26. The sleeve 39, is provided with operating lugs, 39^b, 39^c (see Fig. 10^a), differently positioned circumferentially of said sleeve, and adapted to act as moving elements for moving said sleeve 39,

and its shaft 37, longitudinally in opposite directions in a manner hereinafter described. The sleeve 40, is also provided with similar lugs 40^b and 40^c, for the same purpose. The shafts 37 and 38, are operated in a manner, hereinafter described for the purpose of shifting the selected transmission gears, and to this end, said shafts are provided, respectively, with shifter forks 41 and 42, the forks 10 of which extend downwardly for engaging respectively, with the shifting collars 8 and 10, of gears 6 and 9, as seen in Fig. 8. The shafts 37 and 38, are also provided with yoke members 43 and 44, respectively, each comprising a pair of collars at the opposite ends of its sleeve 39 or 40, as seen clearly in Figs. 1, 4 and 10, which collars are connected below the sleeve, 39 or 40, by means of connecting portions, 43' and 44'. The connecting portions are cut away to form shoulders, as at 43^a, 43^a, and 44^a, 44^a, Fig. 4 for a purpose hereinafter described. The yoke members 43 and 44 are secured to the shafts 37 and 38, so that when said yokes are moved, the sleeves 25 within the yokes, and the shafts must move therewith.

I will next describe the connections from the arm 22, which is operated by the clutch lever 16, for moving the shafts 37 and 38, together with the shifter forks mounted thereon. Referring to Fig. 4, a vertical operating shaft 45, is operatively connected at its lower end to the end of the arm 22, and passes through a bearing at 46, in the casing 36, and through a bearing 47, in a bracket 48, mounted in the casing 36. Pivotedly connected to said shaft 45, as at 43, are two toggle arms 50, 50, the upper ends of which are provided with cross members 51, 51, adapted to engage the shoulders 43^a, 43^a, and 44^a, 44^a, on the under sides of the yoke members 43 and 44, for the purpose of moving said yoke members, together with the shafts 37 and 38, to neutral positions when said arm 22, and the operating shaft 45 are raised. Pivotedly secured to the upper end of the shaft 45, are two toggle arms 52, 52, also provided in their outer ends with cross bars 53, 53, adapted to slide upon the upper sides of the sleeves 39 and 40, and to engage whichever lug on said sleeves 39 and 40 is turned uppermost by the shifting rack 35, operated by the selector lever 26.

It will, therefore, be seen from the mechanism thus far described that the shifting of the selector lever 26, through the connections hereinbefore described, turns the sleeves 39 and 40, on the shafts 37 and 38, so as to bring uppermost the proper lug on sleeves 39 and 40, as the case may be, to be engaged by one or the other of the cross bars 52, 53; also, that when the clutch lever 16, is depressed, its initial movement disconnects the clutch, C, while the continued movement thereof lifts the arm 22, the shaft 45, and raises the toggle

arms 50, 50, on the under side of the yokes 43 and 44, so as to move said yokes to their neutral positions, which operate to move the shafts 37 and 38, in such a way as to disengage whichever of the transmission gears may be 70 in mesh with each other. Therefore, the simple depression of the clutch lever 16, also operates to disengage the transmission gears, which were operating prior to the depression of the clutch lever. The clutch lever is returned, and the arm 22, depressed by means of a spring 54, around the shaft 45, and seated at its lower end upon a bearing plate 55, and at its upper end bearing against the under side of the casing 36, as clearly shown in Fig. 4. As the clutch lever 16, returns and said arm 22 moves downwardly, together with the shaft 45, under the tension of the spring 54, the upper toggle arms 52, 52, having been raised so that one of the cross bars 85 53, 53, thereof, will be in position to engage one of the lugs on one of the sleeves, 39 or 40, which has been turned uppermost by the operation of the selector lever 26, and will thus move one of said shafts 37 or 38, as the case may be, as hereinbefore described, for the purpose of shifting the gear previously selected by the operation of the selector lever 26. The upper toggle arms 52, 52, are yieldingly connected with the lower toggle arms 50, 50, by means of coiled springs 56, 56, which operate to hold the upper toggle arms down on the sleeves 39 or 40, and the lower toggle arms up against the lower sides of the yokes 43 and 44.

Referring to Figs. 1, 2, 3 and 4 there is mounted along side of the rack bar 35, in the casing 36, a square shaft 57, provided with a downwardly depending finger 58, adapted to be engaged by one of the neutralizing toggle arms 50, with each depression of the clutch member 16, for the purpose of rocking said square shaft 57. Secured to the rack bar 35, is a shifting yoke 59, shown in Figs. 1, 2 and 3, which engages a downwardly depending finger 60, slidably mounted on the square shaft 57, for the purpose of moving said finger on said shaft to different positions, according to the distance the rack bar 35, may be shifted in the operation of the selector lever 26. Said finger 60, is movable on said shaft 57, from its neutral position, as shown in Fig. 3, in either direction and to positions adapted to register with the ends of three push rods, 61, 62 and 63, or to register with a crank 64, mounted on a rod 65, directly beneath the rack 35, as shown in Figs. 1, 2 and 3. When either of the push rods 61, 62 or 63, is operated, according to the position of the operating finger, 60, controlled by the rack 35, it operates bell crank 61^a, 62^a or 63^a, which bell cranks are also connected, respectively, with operating or pull rods 66, 67 and 68, while the rods 65, operated by the crank 64, at its opposite end is provided with an 130

upwardly projecting crank arm 69, which is connected by means of a link, 70, to the upper end of a rocker lever 71, shown in Fig. 7, which is pivoted intermediate its ends to a bracket 72 and the lower end of which is pivotally connected to a clutch thrust member 73, of a clutch element 74, the latter of which is shown in Fig. 12, which clutch is operated for a purpose hereinafter again referred to.

I will now describe the mechanism for synchronizing or co-ordinating the speeds of the transmission gears which are to be moved into mesh with each other, in order to facilitate the operation of shifting said gears into mesh with each other while they are running.

Referring now particularly to Figs. 1, 10, 12, 15 and 16, the synchronizing mechanism is mounted in the casing 2, and comprises a shaft 75, which extends through a sleeve 76, and is provided at its enlarged end 77, with a clutch element 79, keyed thereto as at 78. The sleeve 76, through which said shaft 75 extends, is provided at its inner end with a bell shaped drum 80, said drum being closed at its outer end with a driving plate 81, secured thereto around its circumference in any suitable manner. Said driving plate 81, has a hub-like portion 81^a, on which is mounted a driving gear 82, said hub-like portion 81^a, and said drive gear 82, being supported on a short shaft 83, in alignment with the shaft 75, and adapted to be locked thereto, by means of the clutch element 74, engaging with the clutch element 79. Said clutch element 74, is operated by a thrust member 73, with which is connected an operating yoke 71^a, on the lower end of the rocker lever 71, as clearly shown in Figs. 12 and 13, thus making it possible by the operation of said lever 71, to engage the clutch element 74, with the clutch element 79, and thereby lock together for direct drive, the gear 82, drive plate 81, and the shaft 75. The clutch element 74, is normally held out of engagement with the clutch element 79, by means of a coiled spring 84, mounted therein. It will be noted from Fig. 12, that the clutch element 74, has bosses 74^a, 74^b, which project through openings in the drive plate 81, and by means of which it is moved.

The gear 82, as seen more clearly in Fig. 1, meshes with an idler 85, mounted in the casing 2, which idler meshes with a gear 86, mounted on the square shaft 7. Attention is called to the fact that this end of the shaft 7, is connected with the drive shaft of the vehicle, and would, therefore, be driven by the movement of the vehicle, and not from the clutch gear 4. When the clutch element 74, is in its normal position, it is turned independently of the clutch element 79, by the drive plate 81, driven by the gear 82, the bell-shaped drum 80, and its sleeve 76, turning therewith on the shaft 75. When the clutch

74, is shifted into engagement with the element 79, the shaft 75 is driven therewith from the gear 82. Mounted to turn on the sleeve 76, is a sleeve 87, provided with a drum 88, which partially overlies the bell-shaped drum 76. Mounted to turn on the sleeve 87, is a sleeve 89, provided on its end with a drum 90. Mounted on the sleeve 89, is a sleeve 91, which lies partially within the drum 90, and is provided with a drum 92. The drums 88, 90 and 92, are substantially of the same diameter, as will be clear from Fig. 12. Keyed to the outer end of the sleeve 76, is a gear 76^a. On the outer end of the sleeve 87, is a gear 87^a approximately of the same diameter as the sleeve itself. On the end of the sleeve 89, is a similar gear 89^a, and on the sleeve 91, is another similar gear 91^a. Mounted on the shaft 75, is a gear 93, to which is secured a disc 94, provided at diametrically opposite sides with the bearing pins 95, 95, Fig. 14. Mounted on the bearing pins 95, 95, is a cluster of gears 96, 97, 98 and 99. The gear 96, meshes with the gear 76^a, on the end of the sleeve 76. The gear 97, meshes with the gear 87^a, on the sleeve 87. The gear 98, meshes with the gear 89^a, on the sleeve 89, and the gear 99, meshes with the gear 91^a, on the sleeve 91.

In order to hold either of the drums 88, 90, or 92, a brake mechanism is provided for each, clearly shown in end elevation in Fig. 15, and top plan view in Fig. 16, and each comprising a pair of brake levers, 100, 100, provided with brake shoes 101, 101, said 98 levers being pivotally connected at their lower ends, as at 102, 102, and at their upper ends connected by means of links 103, 103, with a rocker arm 104, pivoted intermediate its ends at 105. Said rocker arms 105 105, are connected, respectively, with the pull rods 68, 67 and 66, by means of turn buckles, as at 106. Thus the operating mechanisms for the brake shoes 101, 101, are connected through the pull rods 66, 67 and 68, 110 and their connections, hereinbefore described, for operation by the push rods 61, 62 and 63, which are selectively operated by the finger 60, the position of which is controlled by the position of the rack bar 35, 115 which is controlled from the selector lever 26. Therefore, when the selector lever 26, is moved to one of its selecting positions, it operates through its connections to set mechanism for operating the brake shoes on one of the drums 88, 90, or 92, whereby to hold the selected drum from rotating. When a direct drive, or a high speed, selection is made, the rack 35, is so moved that the finger 60, thereon operates on the crank 64, to rock 120 the rod 65, and its connections for engaging the clutch elements 74 and 79, as hereinbefore described.

I will now describe in detail the operation of the synchronizing mechanism, by means 130

of which the gears selected to be moved into mesh with each other are synchronized from the speed of the vehicle, referring more particularly to Figs. 1, 12, 7 and 8.

5 Assuming that the vehicle is moving, the gear 82, is being driven from the shaft 7, through the gear 86, and the idler 85, which is in mesh with said gear 82. From the gear 82, the drive plate 81, the bell-shaped drum 10 80, with its sleeve 76, and its gear 76^a, on the other end thereof, are all being driven. So long as none of the drums 88, 90 or 92, are held from turning, these drums, and the planetary gear 96, 97, 98 and 99, are driven 15 through the connection of the gear 76^a, with the gears 96, on the bearing pins 95, in the disc 94, and are free to assume the speed and direction thus transmitted through said sleeve 76, and its gear 76^a.

20 Assuming now that it is desired to mesh the intermediate speed gears 6 and 12, Fig. 8, the selector lever 26, is moved to this position, which movement operates through the connections from said selector lever 26, to 25 move the rack bar 35 for the purpose of turning the sleeves 39 and 40, to bring uppermost the lug 39^b for engagement with one of the toggle cross bars 53. This movement also positions the operating finger 60 opposite 30 the push rod 63, through which the brake on drum 88 is applied. As said clutch lever is now depressed, it first disengages its clutch C, and then, through the arm 22, operates the toggles 50, 50, which, in turn, moves the yoke 35 43 or 44 which is out of neutral position, into neutral position for the purpose of moving the transmission gear then operating into neutral position. Said depression of the clutch lever also causes one of the toggle arms 40 50 to engage and rock the finger 58, which operates to rock the shaft 57 and finger 60 for the purpose of supplying the brake to the drum 88. This operates to hold drum 88, together with its sleeve 87, and its gear 87^a, 45 from turning.

The toggle arms 50, 50, are provided with pins 50^a, 50^a, as shown in Fig. 4, which engage the lower sides of the yokes 43' and 44', as said toggles are moved to their uppermost 50 positions, said pins acting as fulcrums for the purpose of moving the cross bars 51, 51, thereof, out of engagement with the shoulders 43^a, 43^a, of said yoke, whereby to permit the upper toggles 52, 52, to be operated in order 55 to move the shaft 37 or 38, in shifting the gears selected to be moved into mesh with each other.

It will be remembered that the vehicle is moving and that the gear 82, drum 80, its sleeve 76, and its gear 76^a, are being turned by the movement of the vehicle according to the speed of the vehicle. As the gear 87^a, is thus held from turning, and the gear 76^a, is being driven by the movement of the vehicle, 60 it will be evident that the gears 96, 97, 98 and 99, which turn as a unit, will be driven from said gear 76^a, and, inasmuch as gear 97 is in mesh with gear 87^a, which is being held, gear 97, must travel around the gear 87^a, and carry with it the disc 94, and the bearing pins 95, mounted therein. This movement of the disc 94 will be determined by the speed of the vehicle being transmitted through small gear 76^a, and gear 96, and gear 97 in mesh with the small gear 87^a, which is being held stationary. This speed is transmitted from the disc 94 to the gear 93, driven therewith and then to the idler gear 107, in mesh with the clutch gear 4, shown in Fig. 1. As the clutch 70 is out of engagement, the clutch gear 4, is driven thereby, and drives gear 11^a on the counter shaft 11, and the gear 12, with which it is desired to move the gear 6 into mesh. It will be remembered that gear 6 and the shaft 7 are being driven by the movement of the vehicle. The gear 12 has been given a pitch line velocity, substantially the same as gear 6, so that as the clutch lever 16 returns, and the toggles 52, 52, operate the gear shifting shaft 37, in a manner hereinbefore described, said gear 6 will be moved into mesh with gear 12, and the intermediate driving speed thus established. The machine is now being driven at the intermediate speed. If 80 it is desired to shift the gears to the high speed, the operation is accomplished in a similar manner. The selector lever 26, is moved to the high position, during which the rack bar 35 turns the sleeve 39, on the shaft 37, to bring lug 39^c, on the opposite end thereof, to the uppermost position, and in position to be engaged by the cross bar 53, on the toggle arm 52, as shown in Fig. 1. Said lug 39^c is not seen on this figure, but is seen in Fig. 10^a. The finger 60 is also moved by the 90 movement of said rack bar 35, to a position opposite the crank 64, for rocking shaft 65. When the clutch lever 16 is depressed, the gears which are in mesh are disconnected by the operation of the toggle arms 50, 50, and the finger 58 on the shaft 57 is rocked, which operates to move the finger 60 for the purpose of rocking shaft 65, for engaging the clutch elements 74 and 79, as will be clear from Figs. 7 and 12, thus making a direct 100 drive from the movement of the vehicle through the gear 82, the clutch members 74 and 79, and the drive shaft 75, to the gear 93, and thence to the clutch gear 4, with which the internal gear 5, is to be moved into mesh. This is easily accomplished for the reason 110 that the shaft 7, and the gear 5, and also clutch 4, are being driven at substantially the same speed. It is apparent that a considerable multiplication of leverage is gained by the lever and link or toggle mechanism for effecting tight frictional engagement of the synchronizing friction members. The other gear shifts are accomplished in the same 115 manner, and while it is even possible to throw 120

the reverse gears into mesh with each other while the vehicle is traveling forward, it is evident, of course, that great care must be exercised, and the clutch be allowed to move 5 very gradually into engagement, which will then operate as a brake in bringing the machine to a stop and immediately reversing the direction of travel without further change. It will be understood, of course, when the 10 reverse drive is desired, the selector lever 26 is moved as before described and the mechanisms operated so as to hold drum 92 from turning. It will be also understood that in order to accomplish a reverse connection of 15 the transmission gears, that the clutch gear 4, must be temporarily reversed in its direction of movement. This is accomplished when drum 92 is held, by the following connections: Referring to Fig. 12 it will be re- 20 membered that gear 82 is being driven by the forward movement of the vehicle and is traveling in the same direction as is the clutch gear 4. Gear 82 is driving drum 80, its sleeve 76, and is, therefore, driving the 25 cluster of gears, 96, 97, 98 and 99. The gear 99 is in mesh with gear 91^a, which is being held with the drum 92. Because of the relative sizes of gear 91^a and gear 99, in mesh with each other, and of gears 96 and 76^a, also 30 in mesh with each other, Figs. 12 and 14, it will be seen that gear 76^a, is driving gears 96 and 99, together around the pin 95, and because of the fact that gear 99 is in mesh with the large gear 91^a, which is being held 35 with the drum 92, gear 99, together with its pin 95, must necessarily move around said gear 91^a, and carry with it the pin 95, the disc 94, and gear 93, around the axis of the shaft 75, in a direction opposite to that of the gear 40 76^a. It will, therefore, be seen that the drive from said gear 93, through the idler 107, to the clutch gear 4, will drive said clutch gear 4, in a direction opposite to that of the drive shaft 7, on which is mounted sliding gear 9, 45 which must be moved into mesh with the reverse idler, 15, in mesh with gear 14, on counter shaft 11. Said idler gear 15, is, therefore, given a direction and speed of travel from the clutch gear, 4, which cor- 50 responds to that of gear 9, being driven by the movement of the vehicle and gear 9 can be readily moved into mesh with said idler. If the clutch is very carefully allowed to engage, it gradually brings the clutch gear, 4, 55 to a stop and immediately reverses the direction thereof, thereby reversing the direction of travel of the vehicle.

It will be appreciated that sufficient time must be provided after the gears have been 60 moved into neutral position by the forward movement of the operating pedal to allow for the proper synchronizing of the gears before movement of the gears into mesh by the return movement of the operating pedal. In 65 other words the movement of the operating

member must be retarded or stopped a sufficient length of time to allow the synchronizing to be accomplished. Ordinarily only a very short time is taken to accomplish this but means should be provided so as to mechanically provide the retarding or stopping action so that it will not be entirely left to the judgment of the operator of the vehicle. The advantages in providing such a mechanical retarding or stopping action of the operating 70 lever in connection with a synchronizing device will be readily appreciated by those experienced in driving motor vehicles over the well known form of gear shift where it is left entirely to the judgment of the operator to bring, as near as possible, the gears to the same speed before movement into meshing position. Assuming that the vehicle is in operation and it is desired to shift gears the preselecting lever 26 is moved 75 to the desired position. The clutch pedal 16 is then depressed or moved forward and in this forward or depressing movement it first releases the clutch, then shifts the gears into neutral position, and then sets 80 the synchronizing mechanism into operation. When the pedal reaches its forwardmost position it is stopped or retarded temporarily, and during said stopping or retarding the gears are held in neutral position and the 85 synchronizing mechanism is in operation. As long as the pedal is held in said forwardmost position the gears will remain in neutral, the synchronizing mechanism will be in operation, and there will be a sufficient lapse of 90 time or retardation to allow the gears to be properly synchronized before the pedal starts on its rearward movement to mesh the gears and to re-engage the clutch. It will thus be seen that on each operation of the pedal to 95 release the clutch and shift the gears there will be some lapse of time to allow for synchronization and although there might be a quick movement of the pedal first forward and then rearward there will nevertheless ordi- 100 narily be sufficient time for the synchronizing to take place. Of course, when traveling at higher rates of speed it may sometimes be found necessary to allow for a longer lapse of time for the synchronizing and this can be accomplished by the operator holding the 105 pedal in depressed position somewhat longer but no matter how long he holds the pedal in such depressed or forwardmost position the gears will be held in synchronism so that when movement takes place to mesh them there will be no gear clash. I have provided, 110 as will be seen, mechanical means for providing this lapse of time when the gears are held in neutral position to allow for proper syn- 115 chronizing. It can be seen that by providing mechanical means whereby the lapse of time takes place that I do away with the necessity of the operator of the vehicle judging at just what point he should stop or hesitate in the 120 125 130

movement of the operating element to allow for the time for synchronizing. The downward or forward movement of the operating pedal will be limited by the movement of the rod 45 as shown or in other suitable manner. While, in my drawings, I have shown the use of a clutch pedal for shifting the gears and setting the synchronizing mechanism into operation it will be understood that no matter what type of gear shifting mechanism or device is used in connection with a synchronizer there must be a sufficient lapse of time, while the gears are in neutral, to allow the proper synchronization to take place.

While I have shown and described one practical embodiment of my invention, I am aware that changes can be made in the general arrangements of the various mechanisms shown in cooperating combination with each other, and that many changes can be made in the details of construction and arrangement of parts, without departing from the spirit of my invention, and I do not, therefore, limit my invention to the details, or the particular arrangement shown and described, except as I may be limited by the hereto appended claims. For example I will employ in some of the claims the general term "lever and link mechanism" associated with certain of the parts to be operated, meaning thereby to embrace the pedal or the like and any suitable mechanical operating connection between the same and the related parts as distinguished, for instance, from simple wiring of an electrical circuit.

I claim:

1. In a power transmission having a clutch, a clutch operating element, and transmission gears, means for successively releasing the clutch, shifting the gears and synchronizing the speed of the gears during movement of the operating element from its normal position, and means for successively shifting the gears and engaging the clutch during the movement of the operating element in returning to its normal position.

2. In a power transmission having a clutch, a clutch operating element and transmission gears adapted to be brought into or out of mesh, means for selecting the gears to be meshed, and independent means for successively releasing the clutch, shifting the gears and synchronizing the speed of the gears by a movement of the operating element in one direction and for successively shifting the gears and engaging the clutch upon the movement of the operating element in the opposite direction.

3. The combination with the shiftable gears of a power transmission mechanism, a clutch and a clutch operating pedal, of a mechanically operated synchronizing mechanism adapted to synchronize the speeds of the gears to be shifted into mesh with each other, said synchronizing mechanism being

automatically controlled and set into action by the depression of the clutch pedal, and means connected with said clutch pedal for automatically shifting the synchronized gears into mesh with each other as said pedal returns after being depressed.

4. The combination with the shiftable gears of a power transmission mechanism, a clutch and a clutch pedal, of a pre-selecting mechanism for determining the gears to be shifted into mesh with each other, a mechanically operated synchronizing mechanism adapted to synchronize the speeds of the gears to be shifted into mesh with each other, means controlled automatically by said clutch pedal for setting said synchronizing mechanism into operation on the gears preselected, said mechanism being set into operation by the depression of said clutch pedal, and means connected with and operated by said clutch pedal for shifting the pre-selected and synchronized gears into mesh with each other as said clutch pedal returns to its raised position, substantially as described.

5. In combination, a clutch mechanism, a transmission mechanism including gears adapted to be meshed, a synchronizing mechanism for synchronizing the speeds of the gears, a pre-selector mechanism for selecting the gears to be meshed, a gear shifting mechanism, and means for operating said gear shifting mechanism and causing said synchronizing mechanism to operate.

6. In combination, gears of varying sizes adapted to be moved into and out of mesh with each other, a synchronizing mechanism for synchronizing the speed of the gears selected, a gear shifting mechanism and a pre-selecting mechanism common to said synchronizing mechanism and said gear shifting mechanism.

7. In combination, gears of varying sizes adapted to be moved into and out of mesh with each other, a pre-selector mechanism for selecting the gears to be moved together, a synchronizing mechanism for synchronizing the speeds of the gears selected, and gear shifting mechanism adapted for shifting said gears and causing the operation of said synchronizing mechanism.

8. In combination, clutch mechanism, a transmission including gears to be meshed, gear shifting mechanism, gear synchronizing mechanism for synchronizing the speeds of the gears to be meshed, and manually operable lever and link mechanism common to all for operating said clutch mechanism, said gear shifting mechanism, and for causing the operation of said gear synchronizing mechanism.

9. In combination, clutch mechanism, a transmission including gears to be meshed, gear shifting mechanism, gear selecting mechanism for selecting the gears to be meshed and means for operating the same,

gear synchronizing mechanism for synchronizing the speeds of the gears to be meshed and manually operable lever and link mechanism common to said clutch mechanism, said

5 gear shifting mechanism and said gear synchronizing mechanism for operating and causing their operation in proper sequence.

10. In combination, a driving element, a driven element, gears thereon adapted to be moved into and out of mesh with each other, means for coordinating the speeds of said gears before they are moved into mesh with each other, an operating lever for moving said gears out of mesh with each other, operating connections from said lever for causing the operation of the means for coordinating the speeds of said gears as said lever is moved in one direction, and operating connections from said lever for automatically moving the coordinated gears into mesh with each other as said lever moves in the opposite direction.

11. In combination, a driving element, a driven element, gears thereon adapted to be moved into and out of mesh with each other, an operating lever for moving said gears, means for coordinating the speeds of the gears to be moved into mesh with each other, said means being set in operation by the movement of said lever in one direction to disengage gears in mesh with each other, and means whereby the movement of said lever in the opposite direction operates to move gears whose speeds have been coordinated into mesh with each other, substantially as described.

12. In combination, a driving element, a driven element, gears on said elements adapted to be moved into and out of mesh with each other, an operating lever for moving said gears, operating connections whereby the movement of said lever in one direction disengages gears already in mesh with each other, means for coordinating the speeds of gears to be moved into mesh with each other, means for previously selecting said gears, said coordinating means being set into operation by the movement of said lever to disengage gears in mesh with each other, and operating connections with said lever for automatically moving the coordinated gears into mesh with each other as said lever is moved in the opposite direction, substantially as described.

13. In an automobile, in combination with the transmission gears and clutch pedal thereof, a gear synchronizing mechanism adapted to be automatically controlled from said clutch pedal when the pedal is operated in one direction, and operating connections from said clutch pedal for automatically shifting the gears whose speeds have been synchronized into mesh with each other with the movement of said clutch pedal in the opposite direction.

14. In an automobile, in combination with the transmission gears and clutch pedal there-

of, a synchronizing mechanism adapted to be automatically controlled from said clutch pedal for synchronizing the speeds of gears to be moved into mesh with each other, a pre-selecting mechanism common to said gears 70 and said synchronizing mechanism for previously selecting the gears to be synchronized and moved, and operating connections from said clutch pedal for automatically shifting the gears whose speeds have been synchronized 75 into mesh with each other with the return movement of said clutch pedal.

15. In an automobile, in combination with the clutch, clutch pedal, transmission gears and driving connections to the rear axle of said automobile, of a gear synchronizing mechanism and means controlled from the clutch pedal during the clutch releasing movement for operating said synchronizing mechanism from said rear axle for synchronizing 85 the speeds of the gears to be moved into mesh with each other, and means operated directly by said clutch pedal for automatically moving said synchronized gears into mesh with each other.

16. In a motor vehicle, the combination with the clutch mechanism and clutch pedal for operating the same, and transmission gears, of a gear selecting mechanism, means for operating the same, gear synchronizing mechanism adapted to be operated by the movement of the vehicle, and operating connections from said clutch pedal for successively disengaging the clutch and the transmission gears already in mesh when said pedal is depressed and for causing the gear synchronizing mechanism to operate, and connections for moving the selected gears into mesh with each other and again engaging said clutch when said clutch pedal is returned to 100 its normal position, substantially as described.

17. In a device of the character referred to, a plurality of gears adapted to be moved into and out of mesh with each other, a mechanically operated synchronizing mechanism for automatically synchronizing the speeds of the gears to be moved into mesh with each other, whereby to facilitate their intermeshing, means for moving said gears out of mesh with each other, said means causing the operation 110 of said synchronizing mechanism during its initial movement, and means whereby the return movement of said gear moving means operates to automatically move into mesh with each other the gears whose speeds have 115 been synchronized.

18. In combination with gears to be shifted, shifting members to move therewith, connections therefrom to said gears, and means for moving said shifting members in opposite 125 directions comprising a set of toggles engageable with the shiftable member, one set of toggles being above said shifting members and the other set of toggles being below, and a transverse operating member connected with 130

- said toggles for operating them in opposite directions.
19. In combination with gears mounted to be shifted, shifting members to move therewith, connections therefrom to said gears, a clutch pedal, an operating member connected to be operated by said clutch pedal, upper and lower sets of toggles connected at their ends to said operating member and at their opposite ends to said shifting members, whereby to be operated in opposite directions on said shifting members, substantially as described.
20. In combination with gear shifting, parallel bars, means for shifting said bars in opposite directions comprising a set of toggle members above the same and a set of toggle members below the same, a transversely moving member connected to one end of each of said toggle members, the opposite ends of said toggle members being connected for moving said shifting bars, and a lever for operating said transversely moving member.
21. In a device of the character referred to, gears adapted to be moved into and out of mesh with each other, an operating lever, shifting elements adapted to be moved in opposite directions, toggle elements above and below said shifting elements for moving the same, and connections from said operating lever to said toggle elements, whereby the operation of said lever in opposite directions operates said shifting elements, substantially as described.
22. In a device of the character referred to, gears adapted to be moved into and out of mesh with each other, means for synchronizing the speeds of said gears, shifting elements adapted to be moved in opposite directions, connections therefrom to said gears, toggle elements connected with said shifting elements for moving the same, an operating lever, and operating connections from said lever to said toggle elements for operating the same, said operating lever functioning to move gears out of mesh as it is moved in one direction and functioning to move the gears whose speeds have been synchronized into mesh with each other as it is moved in the opposite direction, substantially as described.
23. A transmission gearing comprising power gears, means for synchronizing the power gears to intermeshable peripheral speed, a common operating lever for controlling both the power gears and the synchronizing means, means for operating the synchronizing means during initial movement of the operating lever, the operating lever being ineffective to move the power gears from neutral position during synchronizing, and means for producing engagement of the gears upon additional movement of the lever.
24. A transmission gearing comprising power gears, means for synchronizing the power gears to intermeshable peripheral speed, a common operating lever for controlling both the power gears and the synchronizing means, means for selectively operating the synchronizing means during initial movement of the operating lever, the operating lever being ineffective to move the power gears from neutral position during synchronizing, and means for selectively producing engagement of the gears upon additional movement of the lever.
25. A transmission gearing comprising main driven shaft gears and main countershaft gears, means for synchronizing the peripheral speeds of any selected gear on the main countershaft to substantially the speed of the corresponding gear on the main driven shaft, said synchronizing means including gearing in continuous engaging relation with the main countershaft, gearing in continuous driving relation with the main driven shaft, and clutch means adapted to connect said countershaft and said main driven shaft through said gearing.
26. A transmission comprising a plurality of power transmission members, some of said members being shiftable, means for synchronizing the engaging portions of said members before they are connected, a common operating lever for the power transmission members and the synchronizing means, and means associated with the lever whereby said synchronizing means is caused to operate prior to the lever becoming effective to move the shiftable members into engagement, said last mentioned means permitting the shiftable members to remain at rest until the synchronizing means is operated.
27. A power transmission including a driving element, a driven element, power transmission members mounted on said elements, operating means for moving certain of the members for establishing the driving relation between the elements, means for synchronizing the members to intermeshable speed, and means in the path of movement of the operating means adapted to indicate to the operator the place of lull to allow for the proper synchronizing prior to the members assuming the driving relation.
28. A power transmission including a driving element, a driven element, power transmission members mounted on said elements, means for moving certain of the members for establishing a driving relation between the elements, means for synchronizing the members to intermeshable speed, and means for offering an appreciable impedance to the operation of the moving means after the synchronizing means is in effective operation so that sufficient time may be allowed for the proper synchronizing prior to the members assuming the driving relation.
29. In a power transmission gearing including a shiftable element and synchronizing means, means for effecting synchronization and operating the shiftable element by

successive movements of the operating means in opposite directions, and means for retarding the movement of the operating means, after the synchronizing means is in operation.

5. 30. A power transmission including a driving element, a driven element, power transmission members mounted on said elements, means for moving certain of the members for establishing a driving relation between the elements, means for synchronizing the members to intermeshable speeds, and means for retarding the operation of the moving means, after the synchronizing means

10 is in operation, to allow for the proper synchronizing prior to the members assuming the driving relation.

15 31. A power transmission including a driving element, a driven element, power transmission members mounted on the said elements, means for moving certain of the members for establishing a driving relation between the elements, means for synchronizing the members to intermeshable speeds, 20 said synchronizing means being set into operation by the moving means for the transmission members, and means for retarding the operation of the moving means after the synchronizing means has been set into operation to allow for proper synchronizing prior to the members assuming the driving relation.

25 32. A power transmission gearing including gears to be meshed, one of which is shiftable relative to the other, means for synchronizing the speeds of the gears, actuating means for operating the synchronizing means and shiftable gear, and means associated with said actuating means allowing 30 operation of the synchronizing means without movement of the shiftable gear.

30 33. A power transmission gearing including gears to be meshed, one of which is shiftable relative to the other, means for synchronizing the speeds of the gears, actuating means for operating the synchronizing means, actuating means for the shiftable gear, and means whereby the synchronizing actuating means is operated in advance of the 40 actuation of the shiftable gear.

35 34. A transmission gearing including gears adapted to be meshed, one of which is movable relative to the other, and synchronizing means for synchronizing the speeds of the gears, a movable member for operating the shiftable gear, actuating means adapted to move the movable member, and means adapted to allow a limited relative movement between said movable member and the 45 actuating means therefor.

40 35. A power transmission gearing including a shiftable element, synchronizing means for the gearing, means for actuating the shiftable element and synchronizing means, and means permitting lost motion in the actuat-

ing means whereby the synchronizing means may be actuated prior to actuation of the shiftable member from neutral position, said last mentioned means allowing the shiftable element to return to neutral position without lost motion.

50 36. A power transmission gearing including a shiftable element, synchronizing means for the gearing, common means for actuating the shiftable element and synchronizing means, and means associated with the actuating means whereby the synchronizing means is held in operation until the gearing approaches operative position.

55 37. A transmission gearing including shiftable gears, means for synchronizing the gears to intermeshable speeds, a lever, means associated with the lever, to shift the gears into neutral position and set the synchronizing means in operation in one movement and in an additional movement to shift the gears into operable position, and a stop arranged to function between the two movements of the lever.

60 38. A transmission gearing including shiftable gears, means for synchronizing the gears to intermeshable speeds, a lever, means associated with the lever, to successively shift the gears into neutral position and set the synchronizing means in operation in one movement and in an additional movement to successively shift the gears into operable position and release the synchronizing means, and retarding means provided to retard the movement of the lever after engaging the synchronizer.

65 39. A transmission gearing including shiftable gears, means for synchronizing the gears to intermeshable speeds, a lever, means associated with the lever, to shift the gears into neutral position and set the synchronizing means into operation in one movement and in a reverse movement to shift the gears into operable position and to release the synchronizing means, and means to positively stop the first movement of the lever prior to its reverse movement.

70 40. In a power transmission having a clutch, a clutch operating element, and transmission gears, means for successively releasing the clutch, shifting the gears and synchronizing the gears to intermeshable speeds during the movement of the operating element from its normal position, means for stopping the movement of the operating element after the synchronizing means has been set into operation, and means for successively shifting the gears and engaging the clutch during the movement of the operating element in returning to its normal position.

75 41. A power transmission gearing including a shiftable element and synchronizing means, means for actuating the shiftable element to place the gearing in driving relation, means for actuating the synchronizing means,

and means associated with said shiftable element actuating means for retarding the movement thereof after the synchronizing means is in operation and prior to the gearing as suming a driving relation.

42. In a transmission gearing, the combination with a clutch, gear shifting mechanism and gear synchronizing mechanism, of actuating means common to the clutch and gear shifting mechanism to cause the operation of the synchronizing mechanism.

43. In a power transmission gearing the combination with a clutch, gear shifting mechanism, and gear synchronizing mechanism, gear selecting mechanism, and operating means common to the clutch and gear shifting mechanism to cause the synchronizing mechanism to operate.

44. A power transmission including a clutch and power transmission elements, one of said elements being shiftable relative to the other, means for synchronizing the speeds of the elements and common means for operating the clutch, shifting the shiftable elements and controlling the operation of the synchronizing means.

45. A power transmission including clutch mechanism and power transmission elements, one of said elements being shiftable relative to the other, means for synchronizing the speeds of the elements, means for operating said clutch mechanism, and means connected with the clutch operating mechanism and functioning on the operation of the same for shifting the shiftable element and controlling the synchronizing means.

46. A power transmission mechanism including a pair of shafts, means associated with the shafts adapted to establish a drive therebetween, manually operable means for connecting and disconnecting said drive, synchronizing means for establishing the desired speed relation between the shafts before they are placed in driving relation, and means associated with the mechanism to cause at least a momentary pause in the operation thereof to allow time for synchronization.

47. In a power transmission, a pair of main shafts, means associated with the shafts adapted to establish a drive therebetween, manually operable means for connecting and disconnecting said drive, synchronizing means for establishing the desired speed relation between the main shafts before they are placed in driving relation, and resisting means associated with the component parts of the mechanism to sensibly indicate to the operator the position of the manually operable means when synchronization is complete.

48. In combination with gears adapted to be moved into and out of mesh with each other, a synchronizing mechanism for the gears to be meshed, said mechanism including a clutch, an epicyclic gear train, and

means operable by the clutch for holding certain of the gears of the epicyclic gear train to coordinate the speeds of the gears to be moved into mesh.

49. A power transmission including clutch mechanism and power transmission gearing elements, one of said elements being shiftable relative to the other, means for shifting the shiftable element, means for synchronizing the speeds of the elements, means for operating said clutch mechanism, means operatively associated with the clutch operating means whereby the clutch operating means controls the synchronizing means, and means formed and adapted to normally compel a momentary retardation in the operation to insure a synchronizing interval prior to operating engagement of the gearing elements.

50. A power transmission mechanism including a pair of main shafts, gears on said shafts adapted to establish a drive between the shafts, means including a control lever for connecting and disconnecting said drive, and synchronizing means for establishing the desired speed relation between the main shafts before they are placed in driving relation, said synchronizing means comprising a conical member, a member normally freely rotatable relative to the conical member, parts of the mechanism being formed and arranged to constitute leverage multiplying means to produce engagement between the conical member and the normally freely rotatable member during the synchronizing period.

51. The combination with a power transmission including a pair of shafts, gears on said shafts adapted to establish a drive between the shafts, means for connecting and disconnecting said drive, of synchronizing means adapted to establish the desired speed relation between the main shafts before they are placed in driving relation, said synchronizing means comprising a conical member, a member normally freely rotatable relative to said conical member, and means for moving one of the members longitudinally relative to the other to produce engagement and disengagement of the members.

52. The combination with a power transmission including gears adapted to be moved into and out of mesh with each other, of means for synchronizing the speeds of the gears to be moved into mesh, said synchronizing means including a conical member, a member normally freely rotatable relative to the conical member, means to produce engagement between the conical member and the normally freely rotatable member, means for moving the preselected gears into mesh, and preselection means common to both the gear moving means and synchronizing means.

53. In a gear transmission mechanism, in combination with gears to be shifted into and out of mesh with each other and a lever for

- shifting them, of a preselecting device for determining the gears to be moved into mesh, said device including a plurality of members connected with the gears to be moved, and movable to different positions to selectively determine the gears to be moved, a selector lever with connections for moving said members, a synchronizing device for synchronizing the speeds of the selected gears, connections from the selector lever for selectively setting the synchronizing device to act on the selected gears, said synchronizing device including a longitudinally adjustable member moved by the selector lever, clutch means operable by said longitudinally adjustable member, and connections from the lever for moving said gears for operating said adjustable member and its connections to operate the clutch means of the synchronizing device.
54. A power transmission gearing including an operating lever, a shiftable element and synchronizing means, devices for operating the synchronizing means, a movable member for operating the shiftable element, and common means operable by the operating lever for actuating the operating devices and the movable member.
55. Power transmission mechanism comprising drive and driven members, a shiftable element operatively associated with said members for establishing a driving relation therebetween, synchronizing means including a pair of coacting conical friction elements for establishing the desired speed relation between said members before said driving relation is established, a driving connection between one of said friction elements and one of the members, said driving connection being independent of the shiftable element, and means for effecting operation of the synchronizing means and shifting the shiftable element.
56. A transmission including intermeshable power gears, one of which is shiftable relative to the other, means for synchronizing the speeds of the gears before they are meshed, a rocker arm, means engageable with the rocker arm for operating the synchronizing means, and common means for operating the rocker arm to operate the synchronizing means and for shifting the shiftable gear.
57. In a power transmission gearing including shiftable means and synchronizing means, and means for operating the shiftable means and effecting synchronization, said last mentioned means including a slideable shifter rod, means connected to the shifter rod for operating the shiftable means, and a member mounted on a horizontal axis for swinging movement and adapted for operation by the shifter rod for operating the synchronizing means.
58. In a power transmission gearing including shiftable means and synchronizing means, and means for operating the shift-
- able means and effecting synchronization, said last mentioned means including a slideable shifter rod, means connected to the shifter rod for operating the shiftable means, and a member mounted on a horizontal axis for swinging movement and adapted for operation by the shifter rod for operating the synchronizing means, a portion of the swinging member spaced from its horizontal axis engaging the synchronizing means.
59. A power transmission including a driving element, a driven element, power transmission members mounted on said elements, means for establishing driving relation between certain of the elements, means for synchronizing the members to intermeshable speed, and means for offering an appreciable impedance to the operation of the moving means after the synchronizing means is in effective operation so that sufficient time may be allowed for the proper synchronizing prior to the members assuming the driving relation.
60. A transmission gearing including shiftable gears, means for synchronizing the gears to intermeshable speeds, a lever, means associated with the lever to shift the gears into neutral position and set the synchronizing means in operation in one movement and in an additional movement to shift the gears into operable position, and means for effecting a moment of reluctance between the two movements of the lever.
61. In a power transmission, a pair of main shafts, means associated with the shafts adapted to establish a drive therebetween, manually operable means for connecting and disconnecting said drive, synchronizing means for establishing the desired speed relation between the main shafts before they are placed in driving relation, and resisting means associated with the component parts of the mechanism to definitely indicate to the operator when the synchronizing means is in effective operation whereby sufficient time may be allowed for the proper synchronizing prior to the members assuming the driving relation.
62. In a power transmission, a pair of main shafts, means associated with the shafts adopted to establish a drive therebetween, manually operable means for connecting and disconnecting said drive, synchronizing means for establishing the desired speed relation between the main shafts before they are placed in driving relation, and means associated with the component parts of the mechanism to definitely indicate to the operator when the synchronizing means is in effective operation whereby sufficient time may be allowed for the proper synchronizing prior to the members assuming the driving relation.
63. In a power transmission mechanism including members adapted for engagement with and from one another, an operating

lever for connecting and disconnecting the drive between said members, synchronizing means engageable frictionally for establishing the desired speed relation between the members before they are connected, a rocking member adapted to be rocked by said lever for effecting tight frictional engagement of the synchronizing means, and means for causing a momentary reluctance to avert premature contact of the driving members.

64. In a power transmission mechanism including members adapted for engagement with and from one another, an operating lever for connecting and disconnecting the

drive between said members, synchronizing means engageable frictionally for establishing the desired speed relation between the members before they are connected, and means for applying multiplied force from the control lever to effect tight frictional engagement of the synchronizing means, inter-related parts normally involving an increased effort beyond that required for synchronization before the driving association of the driving members can be effected.

In testimony whereof I hereunto affix my signature.

EARL A. THOMPSON.
